UNITED STATES PATENT OFFICE.

FRANK C. HAMILTON, OF NEW YORK, N. Y., ASSIGNOR TO EUREKA PROJECTOR DEVICE CO. INC., OF NEW YORK, N. Y., A CORPORATION OF NEW YORK.

SHUTTER FOR MOTION-PICTURE-PROJECTING APPARATUS HAVING INTERLOCKING PARTS AND MEANS FOR MAINTAINING THE PARTS IN ASSEMBLED RELATION AND FOR MOUNTING THE SHUTTER ON A PROJECTING APPARATUS.

1,214,301.

Specification of Letters Patent. Patented Jan. 30, 1917.

Application filed September 30, 1915. Serial No. 53,235.

To all whom it may concern:

Be it known that I, FRANK C. HAMILTON, a citizen of the United States, residing at New York, in the county of New York and State of New York, have invented certain new and useful improvements in shutters for motion - picture - projecting apparatus having interlocking parts and means for maintaining the parts in assembled relation and for mounting the shutter on a projecting apparatus, of which the following is a specification.

This invention relates to the motion picture art, and concerns itself particularly with improvements in revolving shutters for use in projecting apparatus.

One of the objects of the invention is to provide a shutter in which the usual opaque vanes are replaced by glass sectors, or vanes, which, while transparent, cause a destruction of focus or the diffusion of light rays passing through them, and to arrange for ready and effective assembling of such vanes with the usual revolving shutter shaft of a projecting apparatus.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as a part of this specification, and in which I have shown a merely preferred form of embodiment of the invention, Figure 1 is a side elevation of such an embodiment; Fig. 2 is a sectional view, on an enlarged scale, taken on the line 2—2 of Fig. 1; Fig. 3 is a top plan view, partly broken away, of certain of the parts shown in Fig. 2; and Fig. 4 is an end elevation, partly broken away and partly in section, of the parts shown in Fig. 3.

Similar reference characters refer to similar parts.

The numeral 5 indicates a seat member, provided with a plurality of cut-through

seats or slots each of which is intended for dove-tail or interlocking engagement with the coöperant and correspondingly shaped shank of a vane 6. The seat member is 55 transversely centrally bored at 7 to accommodate a sleeve 8, exteriorly threaded adjacent one end at 8^a, and provided with a plurality of slots 8^b as best shown in Figs. 3 and 4. These slots establish a preferably resilient tongue 8^c. A duplicate pair of side shields 9—9', each of the outline indicated in Fig. 1, are centrally bored so as also to take about the sleeve 8 when said side shields are riveted or bolted to the seat member 5 to 65 maintain said seat member and vanes 6 interlocked. Each vane 6 is thicker in its shank than elsewhere, and the arcuate edges of side shields 9—9' are inturned against arcuate shoulders, one carried on each side of each 70 vane and marking the merging of a vane blade into the shank. A trifurcated flat spring 10 is riveted to one of said side shields as shown best in Fig. 1. A collar 11 is fixedly mounted on sleeve 8, and anchored 75 in place by the application of a suitable screw threaded into the recess and bearing against tongue 8^c. The sleeve 8 and its collar 11 may then be slipped on the revolving shutter shaft 12, and said collar is thereupon fixedly adjustable longitudinally of 80 said shaft, by means of a spiral adjustment of set screw 11^b. The setting of this screw frictionally clamps the tongue 8^c of sleeve 8 against the shaft. 85

A fillet or hoop 14 may be employed as shown, passing around the outer arcuate edges of the vanes. Each of the vanes 6, instead of being opaque, is preferably of a transparent material which, when halted 90 predeterminedly transversely of the light rays from the illuminator within the projecting apparatus, diffuses said light rays sufficiently to project onto the usual screen nothing more than an apparently immobile 95 and even area of illumination. Since, therefore, said vanes 6 may most advantageously be constructed of glass, each preferably being a unitary molded piece, it is desirable that a shock-absorbing means be interposed 100 in the means, now being described, whereby the assembled shutter is mounted on the

shaft 12. This shock-absorbing means is provided in the arrangement whereby an adjustment of a nut 13, separated from the adjacent side shield 9 by washer 14, functions to adjust properly the tension of spring 10.

A noteworthy feature of the present invention resides in the arrangement whereby the entire present embodiment, with the exception of sleeve 8, is applicable by shafts 12 of different diameters; since it is only requisite that an interchangeable sleeve 8 be provided which has an inside diameter approximately equal to the outside diameter 15 of the particular shutter shaft 12.

Inasmuch as many changes could be made in the above construction, and many apparently widely different embodiments of my invention could be made without departing 20 from the scope thereof, it is intended that all matter contained in the above description or shown in the accompanying drawings shall be interpreted as illustrative and not in a limiting sense. It is also to be understood that the language used in the following 25 claims is intended to cover all the generic and specific features of the invention herein described and all statements of the scope of the invention which, as a matter of language, might be said to fall therebetween.

I claim:

1. In a built-up rotatable shutter having a plurality of assembled and projecting vanes, a hub portion, and an auxiliary hub portion 35 adapted to be adjustably fixed within the first mentioned hub portion, said auxiliary hub portion including a sleeve, said sleeve carrying a spirally adjustable nut on one end, and an adjustable collar fixable adjacent its other end.

2. In a built-up rotatable shutter having a plurality of assembled and projecting vanes, a hub portion, and an auxiliary hub portion adapted to be adjustably fixed within the 45 first mentioned hub portion, said auxiliary hub portion including a sleeve, said sleeve carrying a spirally adjustable nut on one

end and an adjustable collar fixable adjacent its other end, and a spring interposed between said shutter and the collar. 50

3. In a built-up rotatable shutter having a plurality of assembled and projecting vanes, a hub portion, and an auxiliary hub portion adapted to be adjustably fixed within the first mentioned hub portion, said auxiliary hub portion including a sleeve, said sleeve carrying a spirally adjustable nut on one 55 end, and an adjustable collar fixable adjacent its other end, and a leaf-spring carried by the shutter and straddling said sleeve. 60

4. In a built-up rotatable shutter having a plurality of assembled and projecting vanes, a hub portion, and an auxiliary hub portion adapted to be adjustably fixed within the first mentioned hub portion, said auxiliary hub portion including a sleeve, and carrying 65 means for clamping the first mentioned hub portion on said sleeve and for clamping said sleeve on the shutter shaft, said means including a resilient tongue extending from 70 and longitudinally of the sleeve.

5. In a built-up rotatable shutter, a body portion provided with a seat, a vane having a shank portion adapted to fit said seat and having also a light-diffusing portion, said 75 light-diffusing portion being thinner than the shank and the junction between the shank and the light-diffusing portion being defined by a shoulder on each side of the vane and a shield on each side of the body 80 portion having a flange engaging over the said shoulder.

6. In a built-up rotatable shutter, a body portion provided with a seat, a vane having a shank adapted to fit said seat and having also a light-diffusing portion, and a cover 85 for said body portion, said cover and the vane having interengaging portions.

In testimony whereof I affix my signature in presence of two witnesses.

FRANK C. HAMILTON.
